UNITED STATES PATENT OFFICE.

JASPER DERRY, OF MEDFORD, MASSACHUSETTS, ASSIGNOR TO ANDREW TERKELSEN,
OF BOSTON, MASSACHUSETTS.

WRAPPING OR UNWRAPPING MACHINE.

Application filed March 19, 1926. Serial No. 96,063.

This invention relates to a wrapping or unwrapping machine, the invention being adapted to be applied to a machine whereby spirally wound strips of material, such as 5 cloth strips, may be unwound from pipe, bars, or other articles, and rewound on a roll or spool. The invention is also adapted for use in machines for unwinding a strip from a roll and wrapping it in helical or 10 spiral windings on a cylindrical or annular object.

An object of the invention is to provide an improved machine capable of accomplishing the foregoing purposes in which improved means is provided for supporting the work or article to be wrapped or unwrapped, 15 said means being movable or adjustable upon varying the angle of lead of the wrapping strip relatively to the work. In the present 20 instance this supporting means is in the form of rotatable disks or rolls which not only act as supporting means for the article, but also act to feed the article or work longitudinally during the wrapping or unwrapping thereof. According to the present invention the supporting disks are mounted 25 so as to permit them to be adjusted in different angularly related planes in accordance with different angles or inclinations at 30 which the strip is lead to or from the article or work. The mounting of the supporting and feeding disks is such as to permit them to be automatically moved into different angularly related planes to compensate for variations in the angle or inclination of lead 35 of the strip. Where, for instance, the invention is used for unwinding a strip from the work, the strip will be unwound evenly as a result of this invention and may be wound 40 on a suitable roll or support evenly and smoothly.

A further object of this invention is to provide mechanism adapted either for wrapping or unwrapping the work, wherein 45 the strip may be guided to or from the work at different inclinations or angular leads, and wherein supporting means is provided for the work which is sensitive to angular variations in the strain exerted by the strip 50 on the work, as a result of which the work supporting means will always adjust itself to the proper position for any given angle of lead of the strip.

A further feature of the present invention 55 is the provision of improved operating mech-

anism for winding the strip after being unwrapped from the article, and also the provision of improved means for controlling the speed at which the strip is wound.

Other objects of this invention will appear 60 in the following description and appended claims reference being had to the accompanying drawings forming a part of this specification wherein like reference characters designate corresponding parts in the 65 views.

Fig. 1 is a plan view partly broken away showing a machine embodying my invention.

Fig. 2 is a side elevation of the construction shown in Fig. 1.

Fig. 3 is a detail side elevation showing the mechanism for supporting and feeding the work.

Fig. 4 is a fragmentary end view of the construction shown in Fig. 3.

Fig. 5 is a sectional plan view taken substantially on lines 5—5 of Fig. 3.

Fig. 6 is a fragmentary side elevation illustrating the supporting rolls or disks and the driving means therefor when the machine is utilized for wrapping purposes.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The present machine as illustrated in the drawings is especially adapted for the purpose of wrapping or unwrapping articles such as pipe, bars, etc., but it will be understood that the parts of the machine may be arranged or designed so as to be adapted for use in connection with the wrapping or unwrapping of other types of articles such as annular objects. Heretofore, in order to 100 wrap cloth strips from pipe, the strip being spirally wound on the pipe, it was necessary to accomplish this by hand, and it was found exceedingly difficult to rewind the cloth strip on a support or roll to prevent the strip from becoming wrinkled or creased around the several windings on the roll. Another serious difficulty encountered in unwrapping the cloth strip from the pipe resulted from the fact that the angle of inclination of the 110

windings of the strip on the pipe are not uniform, and it was therefore impossible to automatically unwind the strip and rewind it smoothly and evenly on a support, due largely to the fact that the angle of lead of the strip varied constantly. The foregoing disadvantages are overcome by my invention, and I have provided mechanism by which the strip may be automatically unwound from the pipe or other article irrespective of variations in the angle of lead of the strip, and in which the strip may be wrapped smoothly on a support or roll without wrinkles or creases being formed in the several windings of the strip on the support or roll.

The machine in the present instance is provided with a suitable base or frame 18 carrying the mechanism. Extending from the base is a post or upright 19, and securely fitted within a bore. In the upper end of this post is a vertically extending shaft 20. A bushing 21 surrounds the upper end of the shaft, and freely mounted thereon is a sleeve 22^a of a swinging bracket 22. A ball bearing 23 is interposed between the sleeve 22^a and the shaft 20, and mounted on the upper end of the shaft is a ball bearing cap 24 secured in place by means of a screw 25. The bracket 22 comprises a forwardly extending arm which is bored to receive studs 26 and 27 for a pair of rotatable disks or rollers 28 and 29 respectively. The outer end of the bracket or arm 22 is tapped 30 to receive the threaded end of the shank 30^a of an operating handle 30. It will be seen from the foregoing construction that the bracket 22 carrying the disks 28 and 29 is free to swing horizontally on the shaft 20, and the bracket may be manually shifted by manipulating the handle 30.

Below the sleeve 22^a and loosely mounted on the bushing 21 of shaft 20 is a sleeve 31. This sleeve is tapped at 32^b to receive the threaded end of the shank or rod 32^a of a handle lever 32. Secured to the upper face of the sleeve 31 is a plate 33 which extends above and parallel to the rod 32^a, and terminates in a downwardly bent or offset portion 33^a having a bore through which extends the rod 32^a. A swinging lever 34 is fulcrumed at 35 on the upper face of the plate 33. The longer arm of the lever 34 extends rearwardly a suitable distance and is connected at its end to a vertically extending post 36, the latter being secured to the outer end of the swinging bracket 22. The shorter arm of the lever 34 at the opposite side of the fulcrum 35 is connected at 38 to one end of a tension spring 37, the opposite end of the spring being connected at 39 to the plate 33 near the turning axis of the sleeve 31.

The tapped hole 32^b into which the forward end of the lever 32^a is threaded extends through the sleeve 31, so that by turn-

ing the handle 32 far enough the forward end of the rod or lever 32^a will act as a set screw and bind the sleeve 31 in fixed and adjusted position on the fixed bushing 21 of the shaft 20.

From the foregoing it will be seen that upon turning the handle 32 so as to loosen the sleeve 31, the latter may then be turned or rotated to the desired position about the shaft 20. Thereupon the sleeve 31 may be secured in this adjusted position. The spring 37 acts to yieldingly maintain the lever 34 in alignment with the points 35 and 39, and hence when the handle 32 is swung laterally from the position shown in Fig. 5 thereby rotating the sleeve 31, the action of the spring 37 will be to urge the lever 34 into alignment with the handle lever 32, thus swinging the arm 22 which carries the disks 28 and 29.

In the present instance where the strip is to be unwrapped from an elongated article, such as the pipe W, a series of spaced supports are provided for the work. The machine may be provided therefore with a plurality of pairs of disks 28 and 29, 28^a and 29^a, etc., two pairs or sets being shown by way of example in Fig. 1, and the work is therefore supported at spaced intervals along its length. The supporting arms 22 for the several pairs of disks 28 and 29, 28^a and 29^a, etc., are connected together for simultaneous swinging movement by means of a longitudinally extending connecting rod 40 which extends through the posts 36 of each supporting unit. From this construction it will be seen that the supports for the several sets of disks will have a common swinging movement and all may be simultaneously adjusted by means of a single controlling mechanism, shown in Fig. 3, which may be carried by one of the sets only.

Where the machine is used for unwrapping purposes the article W which is spirally wrapped with a strip S is placed in position upon the several pairs of supporting disks 28, 29, 28^a and 29^a as shown in Fig. 1. The strip S is led from the work W over the curved edge 100 of a guide 101 (see Fig. 1) and thence is carried through a receptacle 64 containing water for moistening the cloth strip. The strip passes under a guide 65 and over a similar guide 66 carried by a supporting bracket 72, and thence the strip is guided to the stud or roller 52 by means of guides 67, 68, 69 and 70. As hereinafter described the roller 52 is rotated for winding the strip thereon.

The winding mechanism is driven from a suitable motor 41 mounted on the base 18 of the machine. A driving shaft 42 is operated from the motor and is provided with a longitudinal keyway 43, the drive shaft being supported at its outer end within suitable bearings in a bracket 44. Slid-

ingly mounted on the shaft 42 and having a key fitting into the keyway 43 is a driving disk 45 which is adapted to frictionally engage the face of a driven disk 46 having a hub 47^a keyed to a cross shaft 47. A compression spring 48 is interposed between the hub or sleeve 47^a and a collar 49 on the cross shaft so that the driven disk 46 is urged by means of the spring into engagement with the driving disk 45. At the opposite end of the cross shaft 47 is mounted a gear 50 meshing with a larger gear 51 on a stud shaft 76, this shaft carrying at one side of the gears 50 and 51 a guard plate or disk 75, and also carrying the stud or roller 52 upon which the strip is wound.

Mechanism is provided for disengaging the driving and driven disks 45 and 46 and at the same time for applying a braking action to the driven disk 46. As shown in Fig. 1 a brake shoe 53 is mounted at one face of the driven disk 46, this shoe carrying a projecting pin 54, which is housed in a slot in the end of a pivoted cam lever 55 which is swung by means of a handle 56. It will be understood when the lever 56 is swung into the position shown in Fig. 1 the disk 46 will be forced into driving engagement with the disk 45 by means of the spring 48. Upon swinging the handle 56 in the opposite direction the brake shoe 53 will be forced into engagement with the disk 46 resulting in moving the disk against the action of spring 48 away from the driving disk 45; thus at the same time disconnecting the driving disk and applying a braking action to the driven disk. Swinging movement of the handle lever 56 may be limited by means of an arm 57 adapted to engage stops 58 and 59 carried by the frame.

In the present machine the speed of rotation of the stud 52 is automatically controlled in accordance with the diameter of the roll R comprising the several windings of the strip. It will be understood that as the strip is wound on the roller 52 the diameter of the roll R increases, and as the diameter or size of the roll increases it is desirable to decrease the speed of rotation of shaft 76. In the present instance this is accomplished by means of a speed control lever 63 having a part 63^a adapted to constantly engage the peripheral face of the roll R (see Fig. 2). The lever 63 at its lower end is secured to one end of a rock shaft 62 and at the opposite end of this shaft is mounted a lever 61. The upper end of the lever 61 is bifurcated to provide a fork which fits into grooved spool 60 secured to the driving disk 45. From the foregoing it will be seen that as the diameter of the roll R increases the control lever 63 will be swung outwardly, thereby rocking the shaft 62, swinging the lever 61 in the same direction, and shifting the driv-

ing disk 45 away from the axis of rotation of the driven disk 46. This automatically reduces the speed of rotation of the disk 46 and hence the winding roller 52.

From the foregoing it will be seen that the work W is rotatably carried by supporting means which is free to move into various positions. Before commencing the unwrapping operation the several sheets, or pairs or disks 28 and 29 are positioned at an angle corresponding approximately to the angle of inclination of the strip S as it is led off from the work W. This approximate positioning or adjustment of the supporting and feeding rolls 28 and 29 is accomplished as previously described through the handle lever 32. The strip is then threaded through or over the various guides to the stud or roller 52. The machine is started by swinging the lever 56 into position as shown in Fig. 1. As the strip is spirally unwound from the work W the latter will be fed lengthwise by means of the disks 28 and 29. These disks will automatically assume a position in which the planes of the disks will extend parallel to the angle of inclination of the strip as it is led off from the work, or in other words the angle of lead of the strip will determine the angle or inclination of the supporting and feeding disks. Since these disks are mounted so that they will be sensitive to very slight pressure, any variation in the angle of lead of the strip on the work during the unwrapping operation will result in causing the work to swing the disks into proper angle, and against the yielding action of the spring 37.

The feeding disks are initially adjusted at the approximate angle or inclination of lead of the strip, and in practice due to the variations in this lead, it is found that the disks will oscillate horizontally back and forth against the action of spring 37 in order to compensate for the varying leads. As a result of this construction the strip will be unwound evenly from the work and by means of the various guides the strip will be conducted without wrinkles to the support 52, and will be wound thereon evenly and smoothly.

Where the machine is utilized for unwinding the strip from the roll R and wrapping it spirally on the work, the driving mechanism for the stud 52 may be disconnected and the disks 28 and 29 may be positively driven. This may be accomplished as shown in Fig. 6. The disks 28 and 29 carry pulleys 80 and 82 and these are rotated in the same direction by means of a belt wheel 77 and cross belts 79 and 81. The belt wheel 77 is provided with a hub 77^a mounted on a cross shaft 78 which is suitably driven from the driving shaft 42.

It is to be understood that by describing in detail herein any particular form, struc-

ture, or arrangement, it is not intended to limit the invention beyond the terms of the several claims or the requirements of the prior art.

5. What I claim is:

1. In a machine for wrapping or unwrapping helical windings of a wrapping strip, the combination of supporting means for the article to be wrapped or unwrapped, 10 guide means for permitting the strip to be led to or from the article at different inclinations or angles, and means for movably mounting said supporting means to permit movement thereof as the angular lead of the strip varies.
2. In a machine for wrapping or unwrapping helical windings of a strip, the combination of supporting means for the article to be wrapped or unwrapped, guide 20 means for permitting the strip to be led to or from the article, and means for permitting said supporting means to swing as the angular lead of the strip varies.
3. In a machine for wrapping or unwrapping helical windings of a strip, the combination of supporting means for the article to be wrapped or unwrapped comprising rollers peripherally engaging the article, and means for permitting said rollers to swing 30 to compensate for variations in the angle of lead of the strip.
4. In a machine for wrapping or unwrapping spiral windings of a strip, the combination of supporting rollers or disks having 35 the peripheries thereof engaging the article to be wrapped or unwrapped, guide means for permitting the strip to be led at different inclinations to or from said article, and means for adjusting the position of said rollers to accommodate variations in the angle of lead of the strip.
5. In a machine for wrapping or unwrapping spiral windings of a strip, the combination of supporting rollers or disks having 45 the peripheries thereof engaging the article to be wrapped or unwrapped, guide means for permitting the strip to be led at different inclinations to or from said article, and means for varying the position of said rollers to cause the same to automatically assume an angular position substantially corresponding to the angle of lead of the strip.
6. In a machine for wrapping or unwrapping spiral windings of a strip, the combination of supporting means for the article to be wrapped or unwrapped including a roller or disk having the periphery thereof engaging the article, guide means for the strip, means for adjusting said roller into angular 60 position approximating the angle of lead of the strip, and means for permitting the roller to yield to conform to the exact angle of lead of the strip.
7. In a machine for wrapping or unwrapping spiral windings of a strip, the combination of supporting means for the article to be wrapped or unwrapped, guide means for permitting the strip to be led at different inclinations to or from said article, and means for adjusting said rollers to accommodate variations in the angle of lead of the strip.
8. In a machine for wrapping or unwrapping spiral windings of a strip, the combination of supporting rollers or disks having 75 the peripheries thereof engaging the article to be wrapped or unwrapped, guide means for permitting the strip to be led at different inclinations to or from said article, means for supporting said rollers to permit them to swing into different angularly related planes, and means for yieldingly adjusting the rollers in any of said angular planes.
9. In a machine of the class described, the combination of a plurality of pairs of 80 rotatable disks, the disks of each pair overlapping to support therebetween the article, and means for swingingly supporting said disks to permit the same to freely swing by the tension of the strip being wrapped or unwrapped.
10. In a machine of the class described, the combination of a plurality of pairs of rotatable disks, the disks of each pair being 85 positioned to support therebetween the article, and means for movably mounting said disks to permit movement thereof to accommodate different angular leads of the strip.
11. In a machine of the class described, the combination of a plurality of pairs of 90 rotatable disks, the disks of each pair being positioned to support therebetween the article, and means for swingingly supporting the disks to permit movement thereof into angular planes corresponding to different 95 angles of lead of the strip.
12. In a machine of the class described, the combination of rotatable members for supporting on the peripheries thereof the article to be wrapped or unwrapped, and means for supporting said members to permit swinging movement thereof in different planes in accordance with different angles 100 of lead of the strip with relation to the article.
13. In a machine of the class described, the combination of pairs of rotatable disks for supporting the article to be wrapped or unwrapped, and means for movably supporting said disks to permit self-adjustment 105 thereof in accordance with varying angles of lead of the strip with relation to the article.
14. In a machine of the class described, the combination of pairs of rotatable disks for peripherally supporting therebetween the article to be wrapped or unwrapped, means for guiding the strip to or from the article as required by variations in the angle 110 of lead, and means for adjusting said disks 115 to accommodate variations in the angle of lead of the strip.

angularly to correspond to the angle of lead of the strip.

15. In a machine of the class described, the combination of a support, a member 5 swingingly carried by said support, a pair of rotatable disks carried by said member and adapted to support the article therebetween, means for adjusting said member and disks relatively to said support, and yielding means connecting said member with said adjusting means to permit restricted yielding movement of the disks.

16. In a machine of the class described, the combination of a plurality of sets of 15 rotatable disks for supporting the article to be unwrapped, a rotatable support for winding in a roll the strip as it is unwrapped from the article, means for rotating said support, means for automatically controlling 20 the speed of rotation thereof, in accordance with the diameter of the roll, and means for permitting movement of said supporting disks in accordance with the various angles of lead of the strip.

25. 17. In a machine of the class described, the combination of supporting means for the article including a disk peripherally engaging the article, means for angularly leading a wrapping strip to or from said article, 30 and movable means for supporting said disk and sensitive to angular variations in the strain exerted by the strip on the article.

35. 18. In a machine of the class described the combination of supporting means for the article including a disk peripherally engaging the article, means for angularly leading a wrapping strip to or from said article, 40 movable means for supporting said disk, and sensitive to angular variations in the strain exerted by the strip on the article, and means for driving said disk.

45. 19. In a machine of the class described the combination of spaced pairs of rotatable disks located in the same horizontal plane and the disks of each pair overlapping to support therebetween the article to be wrapped or unwrapped, means for angularly adjusting said disks in a horizontal plane, and means for guiding a wrapping strip 50 relatively to the article.

55. 20. In a machine of the class described the combination of spaced pairs of rotatable disks located in the same horizontal plane and the disks of each pair overlapping to support therebetween the article to be wrapped or unwrapped, means for angularly and simultaneously adjusting said disks in a horizontal plane, and means for guiding a wrapping strip relatively to the article.

60. 21. In a machine of the class described the combination of spaced pairs of rotatable disks located in the same horizontal plane and the disks of each pair overlapping to

support therebetween the article to be wrapped or unwrapped, means for adjusting 65 said disks horizontally to cause all the disks to extend at a predetermined angle, means for permitting yielding movement of the disks irrespective of said angular adjustment, and means for guiding a wrapping strip 70 relatively to the article.

22. In a machine of the class described, the combination of spaced pairs of rotatable disks located in the same horizontal plane and the disks of each pair overlapping to 75 support therebetween the article to be wrapped or unwrapped, and means for supporting said disks to permit them to swing as the angular lead of the wrapping strip varies.

80. 23. In a machine of the class described the combination of means for supporting the article, a roll adapted to carry a wound strip, means between said roll and article for guiding the strip, driving mechanism 85 for rotating said roll, means for disconnecting said driving mechanism and applying a brake action thereto, and means for permitting angular adjustment of said supporting means.

90. 24. In a machine of the class described the combination of means for supporting the article, including a rotatable disk, a roll adapted to carry a wound strip, means between said roll and article for guiding the strip, driving mechanism for rotating said roll, means for disconnecting said driving mechanism and applying a brake action thereto, means for permitting angular adjustment of said disk, and means for driving 95 said disk.

100. 25. In a machine of the class described the combination of means for supporting the article with a wrapping strip spirally wound thereon, said means including a disk peripherally engaging the article, a roll adapted to wind up the wrapping strip, means for guiding the strip from the article to said roll, means for driving said roll, and means 105 engaging the periphery of the roll and cooperating with said driving means for controlling the speed of rotation of the roll.

110. 26. In a machine of the class described the combination of means for supporting the article with a wrapping strip spirally wound thereon, said means including a disk peripherally engaging the article, a roll adapted to wind up the wrapping strip, means for guiding the strip from the article to said roll, means for driving said roll, means engaging 115 the periphery of the roll and cooperating with said driving means for controlling the speed of rotation of the roll, and angularly movable means for supporting said disk.

In testimony whereof I affix my signature.
JASPER DERRY.
